UNITED STATES PATENT OFFICE.

HENRY C. COLE, OF WALLINGFORD, VERMONT.

SHOVEL.

SPECIFICATION forming part of Letters Patent No. 352,224, dated November 9, 1886.

Application filed August 4, 1886. Serial No. 209,949. (No model.)

To all whom it may concern:

Be it known that I, HENRY C. COLE, of Wallingford, in the county of Rutland and State of Vermont, have invented a new and useful Improvement in Shovels, of which the following is a specification.

My invention is applicable to snow-shovels, and also to shovels which are employed for malt, and which may be used for various other substances.

The invention relates to a shovel comprising a blade of wood, which has its grain commonly extending from side to side of the blade in a horizontal direction, and a handle extending across the front of the blade, and secured thereto midway of its side edges. In shovels of this class the blade has been armed at the bottom edge with a re-enforcing plate or shoe of metal, which in some cases has simply projected slightly beyond the edge of the blade, and in other cases has had its lower edge reverted or turned backward, so as to form a projecting lip underlying the back of the blade. The lower end of the handle has also in some cases been protected by a cap independent of the edge plate, and secured to the handle and blade by a rivet, as shown in my United States Patent No. 265,387. Where the protecting-cap for the handle is thus made separate from the edge plate and secured by a rivet, the cap is liable soon to become detached by reason of its rivet wearing off or breaking, and the cap and its rivet, being raised above the general surface of the blade, are subjected to greatest wear.

One object of my invention is to prevent the protecting-cap which covers the end of the handle from soon becoming detached, as above described, and thereby leaving the handle without any end protection; and to this end one feature of my invention consists in the combination, with a shovel-blade, of wood, and a handle, of an edge plate extending across from side to side of the blade at the front thereof, and having between its ends an outwardly-offset or struck-up portion, forming, in connection with the blade, a socket to receive the end of a handle. In the above combination the end-protection cap for the handle, being formed integral with the edge plate of the blade, is very strong, and the strength which is afforded by the usual number of riv-

ets inserted through the edge plate and blade throughout the entire length of the edge plate is availed of to secure the cap in place.

55

In the case of shovels, to which my invention relates, the grain of the wood usually extends horizontally from side to side, as above described, and in order to prevent splitting of the blade the edges thereof have been grooved, as is shown in my United States Letters Patent No. 266,775, dated October 21, 1882, and in such grooves have been inserted re-enforcing strips of metal, secured in place by rivets passing through the blade and through the strips. 60 Snow-shovels are subjected to very hard usage, and are often placed in such positions that the water drips upon them, and in winter such shovels are for long periods of time in a constantly wet condition, with the wood considerably swelled, while in summer they are allowed to dry out thoroughly, and the wood correspondingly shrinks. Where the rivets, which secure the re-enforcing edge strips in place, are made fast in both the blade and the 65 re-enforcing strips, such extreme shrinkage and swelling of the wood as takes place frequently causes the splitting of the blade, thereby rendering the shovel practically useless; and a further object of my invention is to ob- 70 viate this difficulty.

75

To this end my invention also consists in the combination, with a wood shovel-blade having its grain extending horizontally from side to side, of re-enforcing strips extending vertically at the edges of the blades and slotted at the end or ends, and rivets inserted through the blade and slotted strips and made fast in the wood of the blade, but free to play in the slots in the said strips, as the wood may shrink 80 or swell by atmospheric changes or the different conditions to which it is subjected.

85

In the accompanying drawings, Figure 1 represents a face view of a shovel embodying my invention. Fig. 2 represents a sectional view 90 thereof upon the plane of the dotted line xx , Fig. 1. Fig. 3 represents a sectional view upon the plane of the dotted line yy , Fig. 1, but upon a larger scale; and Fig. 4 represents one of the re-enforcing edge strips detached, and upon the same scale as Fig. 3.

95

Similar letters of reference designate corresponding parts in all the figures.

A designates the blade of the shovel, and B

the handle, which, as here shown, extends across the face of the blade midway between its sides, and which may be secured by rivets or by screws inserted from the back of the 5 blade. The blade is of wood, with its grain extending horizontally from side to side, and is usually of slightly curved form, as shown in Fig. 3.

At the lower edge of the blade is an edge 10 plate, C, which may be secured to the blade by rivets c, inserted through the edge plate and blade, and at its opposite side edges the blade is provided with grooves, in which are inserted re-enforcing strips of metal d, for 15 preventing splitting of the blade when in use. These re-enforcing strips of metal d are secured in place by rivets e, inserted through the wood of the blade and through holes formed in the strips d.

20 The edge plate, C, may be of sheet-iron or other metal, struck up in suitable shape, and it may have its lower edge reverted or turned backward, so as to form a lip, c', for underlying the bottom edge of the blade, as shown in 25 Fig. 3. The handle B is continued downward beyond the upper margin of the edge plate, C, and the edge plate has formed in it between its ends an offset portion or struck-up projection, C', which overlies the end of the handle 30 B, and in connection with the blade forms a socket for the reception of the handle. I have here represented one of the rivets c, which secures the edge plate, C, in place, as inserted directly through the offset or struck-up portion 35 C' and through the handle B. It will be observed that this offset or struck-up portion or projection C' of the edge plate, C, forms a very secure protection of the end portion of the handle, and there is no joint or crevice 40 between the end protection of the handle and the edge plate in which the grass or other refuse may catch, as there is when the end portion of the handle is protected by a cap formed separate from the edge plate and secured in place by a rivet. A very much 45 greater advantage in forming the end protection for the handle integral with the edge plate, C, is that the strength of all the rivets c which are employed to secure the edge plate 50 in place upon the blade is availed of to secure the end protection of the handle in place, and even if the head of the rivet c which passes through the handle becomes worn off, or if it falls out entirely, the end protection of the 55 handle is not lost, but the edge plate and the offset or deflected portions C', which forms the end protection, are still held in place by the four or more remaining rivets.

In shovels of this character, as heretofore 60 made, the rivets e, which pass through the

edge portions of the blade A and the re-enforcing strips d, have been passed or inserted through round holes in both the wood of the blade and the metal strips d, and as the wood of the blade has shrunk or swelled, owing to 65 the varying conditions of its use and to the different atmospheric conditions, the blade has frequently split directly across from side to side, because the metal re-enforcing strips d will not yield to compensate for the swelling 70 or shrinking of the blade.

In order to prevent splitting of the blade under such circumstances, I form in one or each end of the re-enforcing strips d an elongated opening or slot, d', through which the rivet e 75 passes. The rivet or rivets e are fast in the wood of the blade, and as the wood swells or shrinks the rivets e will move in the slots d', and will permit the wood of the blade to freely shrink or swell without any resistance from 80 the rigid re-enforcing strips d. Slots d' might be provided in both ends of the strips d; but this is not necessary, and I have in Fig. 4 illustrated the strips as having a slot, d', in one end, and a round hole for the reception of a rivet in 85 the other end.

What I claim as my invention, and desire to secure by Letters Patent, is—

1. The combination, with the shovel-blade A, of wood, and the handle B, of an edge plate 90 extending across from side to side of the blade at the front thereof and having between its ends the outwardly offset or struck-up portion C', forming, in connection with the blade, a socket to receive the end of the handle, substantially as herein described.

2. The combination, with the shovel-blade A, of wood, and the handle B, of the edge plate, C, extending across from side to side of the blade at the front thereof, having its edge 100 portion reverted or turned backward so as to lap on the back of the blade, and having between its ends the outwardly offset or struck-up portion C', forming, in connection with the blade, a socket to receive the end of the handle, 105 substantially as herein described.

3. The combination, with the wood blade A, having its grain extending horizontally from side to side, of re-enforcing strips d, extending vertically at the edges of the blade and slotted, 110 as at d', and rivets inserted through the blade and slotted strips and made fast in the blade, but free to play in said slots as the wood may shrink or swell, substantially as herein described.

HENRY C. COLE.
